UNITED STATES PATENT OFFICE.

FRANK TOMASEK, OF CHICAGO, ILLINOIS.

DESIGN FOR AN AUTOMOBILE BUMPER.

Application filed August 18, 1922. Serial No. 3,437. Term of patent 14 years.

To all whom it may concern:

Be it known that I, FRANK TOMASEK, a citizen of the United States, residing at Chicago, in the county of Cook and State of Illinois, have invented a new, original, and ornamental Design for Automobile Bumpers, of which the following is a specification, reference being had to the accompanying drawings, forming part thereof.

Fig. 1 is a plan view of my improved design of automobile bumper; and

Fig. 2 is a front view in elevation thereof. The bars *a* and *b* of the bumper are japanned, and the front member *c* and head of the bolts *d* are nickel plated.

I claim:

The ornamental design for an automobile bumper as shown and described.

FRANK TOMASEK.
